VIDEO PHASE METER CABINET OR SIMILAR ARTICLE

John W. Forrest, West Acton, Mass., assignor to Acton Laboratories, Acton, Mass.

Application July 7, 1954, Serial No. 31,306

Term of patent 14 years

(Cl. D26—5)

Fig. 1.

Fig. 2.

Fig. 3.

*Fig. 4**Fig. 5.*Figure 1 is a perspective view showing the left side, top and front of a video phase meter cabinet or similar article incorporating my new design;

Figure 2 is a front view of the cabinet;

Figure 3 is the right end view, the left end is a mirror image thereof;

Figure 4 is a top plan view thereof. The bottom not shown is identical; and

Figure 5 is a rear view of the cabinet.

The essential features of my design reside in the portions shown in full lines.

I claim:

The ornamental design for a video phase meter cabinet or similar article, substantially as shown and described.
